TWO-WAY ENVELOPE

William Morris Rossiter, Albuquerque, N. Mex.

Application September 6, 1932, Serial No. 631,908

1 Claim. (Cl. 229—73)

This invention relates to a two-way envelope.

An object of the invention is to combine in a single envelope the important features that have heretofore been produced only in several envelopes, whereby a most efficient and simple envelope is produced for a two-way use, such for instance, as a creditor sending a bill to a debtor and a debtor returning the bill with check to the creditor in the same envelope.

10 I am aware that many envelopes have been produced, attempting in different ways to facilitate mailing, but I am the first one to produce, in a single envelope, the several features that go to produce a markedly new envelope, resulting 15 in a step forward in the art, of a very useful and meritorious nature.

With the foregoing and other objects in view, my invention comprises certain novel constructions, combinations and arrangements of parts 20 as will be hereinafter fully described, illustrated in the accompanying drawings, and more particularly pointed out in the appended claim.

In the drawings:

Figure 1 is a view in front elevation of an 25 envelope constructed in accordance with the present invention, while

Figure 2 is a rear view of the same.

Figure 3 is a plan view of the single blank, showing the improved envelope, prior to folding.

30 Figure 4 is a sectional view taken on line 4—4, Figure 2, and looking in the direction of the arrows.

Figure 5 is a rear view of the envelope with the top flap in a raised position.

35 Figure 6 is a perspective view of the envelope showing the same partly folded.

Figure 7 is a perspective view of the envelope with the rectangular full-width resealing flap ready to be folded over, while

40 Figure 8 is a view in elevation of the envelope with said resealing flap folded over and sealed upon the face of the envelope, for the return of the same to the sender.

Figure 9 is a view in front elevation of the bill 45 head, to be used in the envelope, while

Figure 10 is a rear view of the same.

Referring to the drawings by numerals, my 50 combined and simplified two-way envelope comprises a front portion 1 having a large sight opening 2 in its lower part of preferably substantially one-half the size of said front portion. This sight opening 2 is covered by a transparent sheet 3, such as cellophane. Integral with the front portion 1 is right hand end flap 4, left hand end flap 5, bottom flap 6 and top flap 7. The end

flap 4 is of the same length as the front portion 1, and is provided with a resealing flap 8, rectangular in shape, and of a length equal to the length of the front portion 1, and of a depth substantially one-half of the front portion, for excellently covering and strengthening the front portion, as clearly shown in Figure 8 when the envelope is resealed and ready to be mailed back to the sender; this is a marked improvement over the prior art. The resealing flap 8 is provided with adhesive material on its inner face along its outer longitudinal edge and also along its two end edges, as clearly shown in Figure 3, so that the fastening in the position shown in Fig. 8 is accomplished in an excellent manner, 60 whereby the portion of said envelope having said large sight opening 2 as well as both ends of said envelope is greatly strengthened against accidental tear.

When the right hand end flap 4 is folded over, 75 as indicated in Fig. 6, then the left hand end flap 5 is brought over, with its single line of adhesive material or glue 9 against the outer face of end flap 4, to seal the two flaps together. Then the bottom flap with its two "glued" edges is 80 brought up against the end flaps 4 and 5, and sealed in this position, as shown in Fig. 2. It will therefore, be seen that the right hand end flap 4 is provided with no adhesive material.

The top flap 7 and front portion 1 is provided 85 with an inner line of perforations 10, and the top flap is provided with a second line of perforations 11 and with a marking line 12. When the envelope blank, Fig. 3, is folded, the top flap 7 is creased along the marking line 12, so that the 90 lines of perforations 10 and 11 register, with the flap sealed upon the end flap 4. Then when the receiver wishes to open the envelope, he tears the strip 13, Fig. 1, along the perforated line which leaves ready access to the envelope.

Then the receiver removes the contents such as the bill-head or bill 14. This billhead 14 contains the name of the receiver, as "John Doe", which is exposed through the sight opening. When the envelope is to be remailed to the sender, say 95

William M. Rossiter, the bill is folded along line 15, Fig. 9, and then placed in the envelope with "William M. Rossiter's" name and address exposed through the sight opening. Then the resealing flap 8 is folded down over the open end of the envelope, covering the old cancelled stamp, as well as substantially the whole of the face of the front portion, near to the top of the sight opening, giving a substantially new and entirely clean front face to the envelope, for the debtor 100 105 110

to place a new stamp on and, if desired, write anything he desires on this full width new surface. In Fig. 1, I have indicated the envelope as it appears received by the debtor, while in Fig. 8, the envelope is shown as when returned to the creditor.

In the prior art many envelopes are shown that contemplate facilitating mailing, but prior to my invention, no one has disclosed, in one single blank all of the important elements that produce a new combination of the specific type herein described and set forth in the following claim.

What I claim is:

15 As a new article of manufacture, a two-way envelope formed from a single blank and comprising a front portion, said front portion provided in its lower half at its lower edge with a

large sight opening of approximately the same size as its lower half, an end flap integral with said front portion and provided at its upper edge with a rectangular reinforcing and resealing flap of the same length as said front portion and adapted to extend entirely across the same, said reinforcing and resealing flap provided with adhesive material along its outer longitudinal edge and its right angular ends, and said rectangular resealing flap secured over the entire upper half of the outer face of said front portion just above said large sight opening, whereby the portion of said envelope having said sight opening as well as both ends of said envelope is greatly reinforced and strengthened against accidental tear, substantially as shown and described.

WILLIAM MORRIS ROSSITER.
